UNITED STATES PATENT OFFICE.

ELIJAH CHETWYND, OF TRENTON, NEW JERSEY.

DESIGN FOR DINNER-WARE.

SPECIFICATION forming part of Design No. 12,576, dated November 22, 1881.

Application filed October 11, 1881. Term of patent 7 years.

To all whom it may concern:

Be it known that I, ELIJAH CHETWYND, of Trenton, in the county of Mercer and State of New Jersey, have invented a new and Improved Design for Dinner-Ware, of which the following is a full, clear, and exact description.

Reference is to be had to the accompanying drawings, forming part of this specification, in which similar letters of reference indicate corresponding parts in all the figures.

Figure 1 is a side view, and Fig. 2 an end view, of a dish in my design.

The body of the dish has straight beveled sides and ends *a*, that flare outward from the upper edge to the outer edge of the bottom *b*. The bottom is slightly rounded and rests on legs *c*. The legs are formed by a continuous flange, with a waving lower edge, that forms corner, side, and end legs. The corners of the body are rounded, and handles *d* are provided on the ends. The cover is formed with a rounded top, *e*, abruptly beveled at the outer edge, *f*, and the edge is formed with a continuous lip or flange, *g*, that overlaps the upper edge of the body. The cover is also provided with a handle, *h*. The handles *d h* are in form

generally of segments of rings, the inner lines being semicircles, or nearly so, while the outer lines are curved slightly outward at the ends, so as to widen the handles at the joint. The outer lines are interrupted by knobs *i*, of which there are two on each handle, and the sides of the knobs are ornamented by roses.

Having thus described my invention, I claim as new and desire to secure by Letters Patent—

1. The design for dinner-ware herein shown and described, which consists of the beveled sides and ends *a* and rounded bottom *b*, forming the body of the dish.

2. The design for dinner-ware herein shown and described, which consists of the waving-edge flange on the dish-bottom, forming legs *c*.

3. The design for dinner-ware herein shown and described, which consists of the rounded top *e* and flanged bevel-edge *f*.

4. The design for dinner-ware herein shown and described, consisting of semicircular handles *d h*, having knobs *i*.

ELIJAH CHETWYND.
